US00D603380S

(12) **United States Design Patent**
Hutchieson

(10) **Patent No.:** **US D603,380 S**
(45) **Date of Patent:** **** Nov. 3, 2009**

(54) **HEADPHONE**

(75) Inventor: **Brendan Hutchieson**, Hong Kong (CN)

(73) Assignee: **Koninklijke Philips Electronics N.V.**,
Eindhoven (NL)

(**) Term: **14 Years**

(21) Appl. No.: **29/328,276**

(22) Filed: **Nov. 21, 2008**

(30) **Foreign Application Priority Data**

May 22, 2008 (EM) 000938329

(51) **LOC (9) Cl.** **14-01**

(52) **U.S. Cl.** **D14/223**
